RIFLE REST

Filed Feb. 6, 1932

UNITED STATES PATENT OFFICE

WILLIAM B. TEAGARDEN, OF SAN ANTONIO, TEXAS

RIFLE REST

Application filed February 6, 1932. Serial No. 591,422.

This invention relates to a rifle rest, and it is an object of the invention to provide a device of this kind constructed in a manner to enable it to be attached to a belt worn by a person in a way to enable the rest to be readily and conveniently swung into desired position with respect to a rifle to facilitate the firing of such rifle.

It is also an object of the invention to provide a device of this kind which is extensible or contractible in order to facilitate the efficacy of the device.

The invention consists in the details of construction and in the combination and arrangement of the several parts of my improved rifle rest whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawing, wherein:

Figure 1 is a view in side elevation of a rifle rest constructed in accordance with an embodiment of my invention;

Figure 2 is a sectional view taken substantially on the line 2-2 of Figure 1 with certain of the parts in elevation;

Figure 3 is an enlarged fragmentary detailed view illustrating the mounting of the rest proper.

As disclosed in the accompanying drawing, 1 denotes an elongated member herein disclosed as tubular and which is provided therealong with a series of longitudinally spaced openings 2 for a purpose to be hereinafter more particularly referred to.

Threaded or otherwise engaged with the outer end portion of the member 1 is a cap 3 having at its axial center a relatively large opening 4. This opening 4 is adapted to receive a lug 5 depending from the central portion 6 of the rifle rest member M. The lug 5 as well as the associated opening 4 are circular in form so that the member M may readily have turning movement.

Contacting with the inner face of the head of the cap 3 is a disk 7, said disk being of a diameter greater than the diameter of the opening 4 so that when said member or disk 7 is anchored as by the screw member 8 to the portion 6 of the member M said member M will be effectively held in assembled relation with respect to the cap 3 and through the instrumentality of the cap 3 upon the member 1.

The member M is U-shaped in form or what might be termed a "long horn" type to facilitate the desired engagement with the rifle.

The member 1 is telescopically received within a second elongated tubular member 9 having extending along its major portion the longitudinally disposed slot 10 which receives an outstanding lug 11 carried by the inner or inserted end portion of the member 1. This lug 11, as herein disclosed, is in alignment with the openings 2 and said lug coacts with the side walls of the slot 10 to hold the members 1 and 9 against rotation one with respect to the other.

The outer end portion of the member 9 has threaded or otherwise engaged thereon a cap 12 carrying a transversely disposed loop member 14 for a purpose to be hereinafter more particularly referred to.

Interposed between the applied cap member 12 and the inserted end of the member 1 is an expansible coil spring 15 the extremities of which preferably carrying the buttons 16. The inner end portion of the member 12 has pivotally engaged therewith, as at 17, an elongated lever or arm 18. This lever or arm 18 is disposed in a direction lengthwise of the member 1 and is provided at one end portion with an angularly disposed finger 19 adapted to pass through the elongated slot 10 and be selectively received in one of the openings 2 whereby the members 1 and 9 will be locked in relative lengthwise adjustment. The end portion of the arm or lever 18 remote from the finger 19 is constantly urged outwardly by the spring member 20 interposed between the member 9 and said end portion of the arm or lever 18. This spring member 20 serves to constantly

urge the finger 19 toward the inserted portion of the member 9 for engagement through an opening 2.

The finger 19 is at the inner end portion of the arm or lever 18 and this is of advantage because as the hand of the user moves outwardly along the member 9 it will readily and conveniently engage the outer end portion of the arm or lever 18 to facilitate the desired inward movement of said portion of the arm or lever to retract the finger 19 from locking engagement with the inserted end portion of the member 1.

In practice a small buckle strap, stout buck-
15 skin string or other suitable flexible member is adapted to be threaded through the loop 14 and securely fastened to a belt worn by a person, said connection being such to allow enough extra play to permit free movement
20 of the rest. This means of attachment allows a firm anchor in desired position with respect to the belt so that when the rest is lifted and a gun placed on it, the belt end will hold the rest in position as a fulcrum and
25 prevent the rest from yielding further backwards or downward. If, in order to properly engage the rifle to effect the desired aim, it is necessary to extend the member 1, as the hand passes out along the member 9 it
30 will come into contact with the lever or arm 18 and thus release the member 1 whereupon the spring 15 will function to automatically throw the member 1 outwardly. Upon release of the arm or lever 18 the finger 19
35 thereof will automatically move in a direction for desired engagement through an opening 2.

It is also believed to be clearly understood that as the member 1 is telescoped within
40 the member 9 the spring 15 will be placed under increased tension.

From the foregoing description it is thought to be obvious that a rifle rest constructed in accordance with my invention is
45 particularly well adapted for use by reason of the convenience and facility with which it may be assembled and operated, and it will also be obvious that my invention is susceptible of some change and modification
50 without departing from the principles and spirit thereof and for this reason I do not wish to be understood as limiting myself to the precise arrangement and formation of the several parts herein shown in carrying out my invention in practice except as
55 hereinbefore claimed.

I claim:-

1. A device of the class described comprising an elongated member, means carried
60 by one end portion of the member for securing the same for swinging movement, a second member slidably engaged with the first named member, means for constantly urging the second named member outwardly with
65 respect to the first named member, and a rifle

rest member carried by the second named member.

2. A device of the class described comprising an elongated member, means carried by one end portion of the member for securing
70 the same for swinging movement, a second member slidably engaged with the first named member, means for constantly urging the second named member outwardly with respect to the first named member, a rifle
75 rest member carried by the second named member, and coacting means carried by the first two named members for locking said members against endwise movement one with respect to the other.

In testimony whereof I hereunto affix my signature.

WILLIAM B. TEAGARDEN.
